UNITED STATES PATENT OFFICE.

EDWARD L. IVES, OF CHICAGO, ILLINOIS, ASSIGNEE TO FREYN, BRASSEUR & COMPANY, OF CHICAGO, ILLINOIS, A CORPORATION OF ILLINOIS.

BLAST-FURNACE STOCK-LINE PROTECTION.

Application filed October 24, 1921. Serial No. 509,774.

To all whom it may concern:

Be it known that I, EDWARD L. IVES, a citizen of the United States, residing at Chicago, in the county of Cook and State of Illinois, have invented certain new and useful Improvements in Blast-Furnace Stock-Line Protections, of which the following is a specification.

This invention relates to a new and improved means for protecting the top portion of blast furnaces known as the stock line, and more particularly to a composition of metal adapted for use in such protection.

As is well known in the art, a blast furnace is lined with refractory brick to resist the heat action of combustion. The coke, ore and limestone or other fluxing material are introduced into the furnace from above, and in the usual form, this material is distributed by means of a bell. This bell throws the material against the sides of a furnace adjacent the top. This portion of the furnace is known as the stock line and protecting means must be provided or otherwise the brick walls are rapidly worn away by the action of the materials impinging against them.

It has been common practice to protect this portion of the furnace by means of cast iron or steel plates or by a continuous ring of cast iron or steel. These methods of protection have not been satisfactory due to the qualities of materials used. If cast iron is used, with its high carbon content, the metal is soft and the carbon which amounts to about 4% is gradually eliminated from the metal causing deterioration and weakening thereof. If steel is used in which the carbon content has been reduced to 1½% or lower, the metal is so soft that it is easily worn away.

It is an object of my invention to provide a material for stock line wear plates which is adapted to give the necessary strength and resistance to wear and abrasion.

It is a further object to provide material of great hardness and toughness whereby the protecting plates may be made relatively light and whereby their cost is reduced.

Other and further objects will appear as the description proceeds.

In order to make clear the application of my invention, I have shown a blast furnace

having stock line protecting plates, in the accompanying drawings, in which— 55

Figure 1 is a somewhat diagrammatic cross section of a blast furnace; and

Figure 2 is a fragmentary section on an enlarged scale showing the stock line protection. 60

As shown in the drawings, the upper portion or stock line section 3 of the furnace is provided with the wear plates 4 having flanges 5 extending inwardly of the brick work to anchor the plates thereto. The 65 plates are placed a small distance apart in order to provide for their expansion when heated. The top of the furnace is provided with the hopper 6, the lower portion of which is closed by the bell 7. It is to be 70 understood that in the operation of the furnace, a charge of ore, stone or coke is placed in the hopper 6 and then is dumped into the furnace by lowering the bell 7. The bell 7 is operated by well known means 75 which form no part of the present invention and have not been shown. This bell distributes the charge throughout the circumference of the furnace throwing it against the plates 4 protecting the stock 80 line.

These plates are formed of a steel having added thereto manganese in percentages running over 3%. The addition of this manganese has been shown by experience to form 85 a steel which resists wear in this application far better than ordinary steel or cast iron. This manganese steel contains less than 1½% of carbon and has the necessary hardness and strength to withstand the wear and tear 90 to which the stock line of the furnace is subjected.

I claim:

1. In a blast furnace, protecting plates located at the stock line thereof, said plates 95 containing in excess of three per cent of manganese.

2. In a blast furnace, steel protecting plates located at the stock line thereof, said plates containing less than one and one-half per cent of carbon and in excess of three per cent of manganese. 100

Signed at Chicago, Illinois, this 20th day of October, 1921.

EDWARD L. IVES.
